UNITED STATES PATENT OFFICE.

WILLARD R. WALKER, OF SYRACUSE, NEW YORK, ASSIGNOR TO THE WALKER BROTHERS COMPANY, OF SYRACUSE, NEW YORK, A CORPORATION OF NEW YORK.

DISH-WASHING MACHINE.

1,397,846.

Specification of Letters Patent. Patented Nov. 22, 1921.

Application filed August 13, 1918. Serial No. 249,645.

To all whom it may concern:

Be it known that I, WILLARD R. WALKER, a citizen of the United States of America, of Syracuse, in the county of Onondaga, in 5 the State of New York, have invented new and useful Improvements in Dish-Washing Machines, of which the following, taken in connection with the accompanying drawings, is a full, clear, and exact description.

10 This invention relates to certain improvements in dish washing machines involving the use of a primary or washing vat and a secondary or rinsing vat arranged side by side and connected in such a manner that the 15 cleaner fluid from the rinsing vat may discharge by gravity directly into the washing vat, the primary object being to render the entire cleansing operations more continuous, expeditious and convenient than has heretofore been practised and at the same time to avoid excessive waste of the water or 20 other cleaning fluid.

Other objects and uses relating to specific parts of the apparatus will be brought out 25 in the following description.

In the drawings:

Figure 1 is a front elevation, partly in section, of a dish washing machine embodying the various features of my invention.

30 Fig. 2 is a detail horizontal sectional view of a portion of one side of one of the vats taken in the plane of line 2—2 Fig. —1— to show the baffle plate across the overflow opening.

35 Fig. 3 is a horizontal sectional view of a portion of the machine beneath the vats taken in the plane of line 3—3 of Fig. —1—.

40 Figs. 4 and 5 are transverse vertical sectional views taken respectively in the planes of lines 4—4 and 5—5 Fig. —3—.

As illustrated this apparatus comprises a table —1—, a pair of upright vats —2— and —3— for the washing and rinsing fluids adapted to contain suitable dish supporting 45 trays —4— shown in part by dotted lines in Fig. —1—, suitable means for supplying the washing fluid to the vats and means for impelling the fluid upwardly from the bottoms so as to impinge against all portions 50 of the dishes or other articles which may be carried in the trays.

The table —1— is supported in a horizontal position upon suitable legs —5— and is provided with similar circular openings

—6— and annular flanges —7— for receiving and supporting the vats —2— and —3— with their upper ends in substantially the same horizontal plane nearly coincident with that of the table.

55 A lower deck or platform —8— is secured to and between the legs —5— in a horizontal plane some distance below the lower ends of the vats for receiving and supporting various parts of the driving mechanism for the impellers hereinafter described and 60 also serving to brace the legs against relatively lateral movement, said legs being additionally braced by horizontal bars —9— in a plane below the deck or platform —8—.

65 In order that the vats —2— and —3— may be additionally supported without perforating or otherwise mutilating the same, I have provided a pair of circular bands —10— each encircling the cylindrical body of one 70 of the vats in a horizontal plane some distance below the table —1— and co-axial with the openings —6—, said bands being secured by bolts or other suitable fastening means —11— to the inner faces of the legs —5— to hold the vats against lateral vibratory movement in their respective openings —6—.

75 The vats —2— and —3— are similar except that they are of different depths or heights, the general construction being substantially the same as that shown and described in my Patent Number 1,070,562, August 19, 1913, 1,158,409, Oct. 26, 1915, 1,224,446, Oct. 23, 1917, 1,259,939, March 19, 1918, and 1,265,843, May 14, 1918, in 80 so far that their main bodies are cylindrical and their upper ends are enlarged at —12— and are provided with lids or covers —13—, the lower ends being provided with conical or hopper shaped bottoms —14— having central bearings —14'— and channels —16— surrounding said bearings.

85 The cylindrical portions of the vats are supported in the openings —6— and rings —7— with their upper enlarged ends —12— resting upon the flanges —7— in substantially the same horizontal plane. The vat —2— is considerably deeper than the vat —3— and may be termed the primary or 90 washing vat, the bottom of which is disposed in a horizontal plane mainly below the bottom of the vat —3— and is provided 95 100 105

with a drainage outlet in the apex thereof communicating with a drainage pipe —15— having a normally closed valve —15'— for controlling the discharge of the washing fluid, said valve being similar to that shown in my Patent No. 1,304,519, issued May 20, 1919.

This vat —2— is also provided in one side with an overflow or outlet —17— in a plane some distance above that of the drainage outlet adjacent the junction of the conical bottom —14— with the cylindrical body and is connected by an overflow pipe —18— with the drainage conduit —15— beyond the valve —15'— where the overflow may have a free exit independent of said valve.

As previously intimated the washing fluid is impelled upwardly by a rotary impeller presently described and in order to prevent undue exit of the upwardly impelled fluid through the overflow —17—, I have provided a baffle plate —19— extending circumferentially across said opening between the inlet in the side thereof and the point of connection of the conduit —18— therewith as shown more clearly in Fig. —2—, the purpose of said outlet being to determine the level of the washing fluid in the vat.

The shallower vat —3— is adapted to contain a rinsing fluid and may be termed the secondary or rinsing vat and like the vat —2— is provided with an inverted conical or 35 hopper-shaped bottom —14— having a central conical bearing —14'— in the apex thereof surrounded by a channel —16— to which is connected a drainage conduit —15— having a valve —15'— for controlling the discharge of the fluid. This vat is also provided with an overflow opening or outlet —17— in a plane some distance above that of the drainage outlet or near the junction of the conical bottom —14— with its 40 cylindrical sides and is connected by a conduit —18— to the drainage conduit —15—. 45

A baffle plate —19— extends across the overflow —17— in a manner and for the same purpose as previously described for .50 the vat —2—.

The drainage conduit —15— leading from the bottom of the vat —3— discharges directly into an inlet —20— in the adjacent side of the bottom of the vat —2— said inlet 55 being disposed in a plane or level between that of the drainage outlet and overflow of the vat —2— so that when the valve —15'— of the vat —3— is open the cleaner rinsing fluid may be discharged therefrom into the 60 washing vat for reuse after which fresh rinsing water may be supplied to the vat —3— through supply pipe —21— which is connected to both vats.

It is now clear that the overflow openings

—17— determine the levels of the fluid in 65
their respective vats so that the liquid level
in the vat —2— will be considerably lower
than that in the vat —3— or in this instance
in approximately the horizontal plane of the
drainage outlet of the vat —3—, both of the 70
overflow openings being disposed at ex-
actly the same elevation from the corre-
sponding drainage outlets thereby maintain-
ing a relatively shallow body of water in
each vat. 75

The dish supporting tray or basket —4— for each vat is similar to that set forth in my Patent Number 1,285,490, issued Nov. 19, 1918, and is supported in a plane above the corresponding overflow outlet —17— 80 and therefore some distance above the bottom of the vat and above the impeller which is movable in the vat, said basket having relatively large openings in its bottom and sides to allow the washings and rinsing fluids 85 to pass therethrough and to contact with all portions of the dishes and other articles supported thereby when the impeller is in motion. On the other hand when the impeller is at rest the dishes and other articles which are carried in the basket above the normal liquid level are automatically drained and dried, when left for a short period of time as for example in the rinsing vat. 90 95

Each vat is provided with a similar rotary impeller blade —22— similar to that set forth in my Patent Number 1,244,446 previously referred to, said impellers being secured to separate vertical shafts which are 10 journaled in the bearings —14'— in the bottoms of their respective vats and are driven by a horizontal shaft —24— through the medium of opposite sets of intermeshing gears —25—. 10

The shaft —24— is journaled in bearings —26— on the lower deck or platform —8— of the main supporting frame and is provided with opposed clutch members —27— feathered thereon in axially spaced relation. 11 A pulley —28— is loosely mounted on the shaft —24— and has the opposite ends of its hub provided with clutch members for co-operative engagement with one or the other of the clutch members —27—, the pulley —28— being connected by a belt —29— to a suitable motor —30— which is also mounted upon the deck or platform —8— as shown more clearly in Fig. —3—.

The clutch members —27— may be operated independently into an out of engagement with the adjacent ends of the pulley —28— by means of separate shifting levers —31— (Figs. —3— and —5—). Each of the clutch members —27— is provided with a relatively rotatable section —27'— within the main section —27—, said sections being provided with radial lugs —32— and —33—.

between which are located coiled springs —34— which serve as shock absorbers in preventing an abrupt start of either impeller or suddenly retarding the motor when either or both of the clutches are thrown into operative engagement with the pulley —28— it being understood that the gears —25— are arranged so as to drive both impellers in the same direction.

10 In operation the soiled dishes and other articles are suitably arranged within and upon one of the trays —4— which is then placed into the vat —2— containing a shallow body of water on the conical bottom thereof between the level of the overflow and drainage outlet, the corresponding valve —15'— being closed. After the lid is placed in operative position the corresponding clutch member is shifted into engagement with the pulley —28—, the motor —30— being then started by the operation of an electric switch —a— Fig. —1— which rotates the corresponding impeller blade —22— to impel the water upwardly through the over-lying basket —4— and against the dishes and other articles which may be carried by the basket, the upward deflection of the whirling water being aided by a series of deflecting plates —22'— which are rigidly secured to the interior of the vats and are similar to those shown in my Patent Number 1,244,446 previously referred to.

This initial washing operation is continued as long as may be necessary to effect a thorough cleansing of the dishes and other articles, after which the clutch may be shifted to its inoperative position to stop the impeller and allow the water to settle and drain back to its normal level.

40 When the dishes are sufficiently drained the basket containing the same is removed from the vat —2— and placed in the rinsing vat —3— where a similar cleansing operation is performed with clean water and if required a second basket containing other soiled dishes may be placed in the vat —2— to be operated upon simultaneously with the rinsing operation. After the dishes in the vat —3— have been thoroughly rinsed the impeller is stopped by the shifting of the corresponding clutch and the dishes are then allowed to drain for a short time whereupon the basket with the clean dishes thereon may be removed and carried to the place of distribution.

The soiled washing fluid in the vat —2— may be drawn off at any time by simply opening the corresponding valve —15'— whereupon the rinsing water which has been previously used in the vat —3— may be diverted therefrom to the vat —2— by simply turning the valve —15'— in the drainage connection between the vats after which the said valve may be closed and fresh rinsing

water supplied to the vat —3— through the supply pipe —21—, the latter being provided with valves —21'— one for each vat to control the supply of fresh water thereto.

What I claim is:

1. In a mechanical dish washer, upright vats supported side by side and provided with conical bottoms having their apexes disposed in planes one above the other, a drainage conduit leading from the higher apex into the conical bottom of the other vat, and an overflow pipe leading from the vat having the higher conical bottom into said drainage conduit.

2. In a mechanical dish washer, upright vats of different depths supported side by side with their upper ends in substantially the same horizontal plane and their lower ends provided with drainage outlets, a drainage conduit leading from the outlet of the shallower vat into one side and above the outlet of the deeper vat, separate valves controlling said outlets, and an overflow conduit leading from one side of the shallower vat into said drainage conduit between the valve and deeper vat.

3. In a mechanical dish washer, a pair of upright vats supported side by side and provided with conical bottoms having drainage outlets in their apexes, a conduit leading from the outlet of one vat into the other vat above the outlet thereof, and an overflow pipe leading from the first named vat into said conduit.

4. In a mechanical dish washer, an upright vat having a conical bottom, an impeller rotatable within the conical bottom about a vertical axis, a drainage conduit leading from the apex of said bottom below the plane of rotation of the impeller, a supply conduit for the washing fluid entering the upright portion of the vat above the conical bottom, and an overflow conduit leading from the vat at a point near the junction of the conical bottom with the upright portion of said vat to limit the rise of the liquid to approximately the level of said junction.

5. In a mechanical dish washer, an upright vat having a conical bottom, an impeller rotatable about a vertical axis within the conical bottom, a drainage conduit leading from the apex of said conical bottom below the impeller, a valve in said conduit, and an overflow conduit leading from the vat at a point near the junction of the conical bottom with the upright portion and connected to the drainage conduit at a point beyond the valve.

6. In a mechanical dish washer, upright vats arranged side by side and provided with conical bottoms in planes one above the other, impellers rotatable within said conical bottoms about vertical axes, drainage conduits leading from the apexes of said conical

bottoms below their respective impellers, the conduit leading from the apex of the higher conical bottom being connected to the other vat, separate valves in said conduits, and separate overflow conduits leading from said vats at points near the junctions of the conical bottoms with the upright portions thereof and connected to the

corresponding drainage conduits at points beyond the valves thereof.

In witness whereof I have hereunto set my hand this 6th day of August, 1918.

WILLARD R. WALKER.
